DESIGN FOR A SEPARABLE BRACELET

John Rubel, New York, N. Y.

Application March 20, 1944, Serial No. 112,963

Term of patent 14 years

(Cl. D45—7)

To all whom it may concern:

Be it known that I, John Rubel, a citizen of the United States, residing in New York city, in the county of New York and State of New York, have invented a new, original, and ornamental Design for a Separable Bracelet, of which the following is a specification, reference being had to the accompanying drawing, forming part thereof.

Fig. 1 is a top plan view of a separable bracelet showing my design.

Fig. 2 is a fragmentary elevational edge view on an enlarged scale of the separable bracelet shown in Fig. 1.

Fig. 3 is a top plan view of the removable center section of the bracelet shown in Fig. 1 in separate position.

Fig. 4 is a fragmentary top plan view of the separable bracelet, with the separable member removed.

I claim:

The ornamental design for a separable bracelet or similar article, substantially as shown.

JOHN RUBEL.
